UNITED STATES PATENT OFFICE.

JOSEPH J. MOSER, OF WEST COVINGTON, KENTUCKY.

CAN-CLOSURE.

No. 823,430.

Specification of Letters Patent.

Patented June 12, 1906.

Application filed July 28, 1905. Serial No. 271,687.

To all whom it may concern:

Be it known that I, JOSEPH J. MOSER, a citizen of the United States, residing in West Covington, in the county of Kenton and State of Kentucky, have invented certain new and useful Improvements in Can-Closures, of which the following is a specification.

It is the object of my invention to provide a new and improved can-closure comprising a can-body whose upper end is turned inwardly toward the longitudinal axis of the can for forming a strengthening-web for said upper end and then upwardly and preferably taperingly toward said longitudinal middle, and terminating in a cut lip extending outwardly of the can-body for forming a tapering mouth, the said tapering mouth receiving inside thereof an oppositely-tapered plug having a depressed web and an upper outwardly and sidewardsly extending double-walled bead, the cut edge of the metal of said plug being inside said bead, the mating side faces of said double-walled bead engaging the side faces of said lip in closing the can, the wall of said depending tapering part of the plug being expanded sidewardsly outwardly under and engaging the sidewardsly inwardly extending web at the top of the can-body, for locking said plug in position on the can-body against outward pressure from the inside of the can, but permitting the release of said plug by a wedging force applied at the top of the can-body against the bead of the plug; and the invention will be readily understood from the following description and claims and from the drawings, in which latter—

Figure 1 is a side elevation of my improved device. Fig. 2 is a vertical cross-section of a portion of the same, showing the plug presented to the mouth of the can-body ready for insertion of the plug. Fig. 3 is a similar view with the plug pressed into the can-body. Fig. 4 is a similar view of the same parts, showing the plug pressed into the can-body, the tapering wall of the plug being provided with an outwardly-extending annular rib taking under the transverse web at the top of the can-body for locking the plug in position; and Fig. 5 is a similar view with the annular groove at the top of the can-body provided with a packing.

1 represents the can-body, which has a mouth formed of an annular wall of sheet metal having a laterally-extending strengthening-web at its bottom. Thus 2 is an annu-

lar rim portion for the top of the can-body, which has an outer depending flange 3 for forming a shoulder 4, upon which the rim portion is supported on the upper edge of the can-body, the rim portion being secured to the can-body by solder or in other suitable manner. The said rim portion has a sidewardsly inwardly extending and slightly downwardly tapering annular part 5, merging into a semibead 6, from the inner edge of which the said rim portion projects outwardly and taperingly toward the longitudinal axis of the can-body for forming the annular wall 7 of the mouth of the can-body, the said annular wall being in the form of an upright frusto-cone and having an outer cut edge 8 of the sheet metal, from which said rim portion is formed. The said cut edge or lip 8 preferably projects above the horizontal plane of the upper edge of the can-body. An intermediate shoulder 9 is thus formed on the rim portion between the annular part 5 and the semibead 6 of the rim portion, the said parts forming a transverse inwardly-extending annular web for the rim portion arranged to transversely reinforce the lower end of the annular wall of the mouth of the can-body for purpose hereinafter explained.

15 is the plug or cover of the can and comprises an annular wall 16, tapering downwardly toward the longitudinal middle of the can and being in the form of an inverted frusto cone at whose smallest diameter there is a transverse web 17, preferably extending below the horizontal plane of the web when the plug is seated, the upper edge of said plug being formed with a bead preferably curved within the groove 11 formed in said web of the can for resting on said shoulder 9 when said plug is seated. The upper edge of the annular wall 16 of the plug is preferably formed into an annular outer double-walled bead 18, as by continuing the upper end of said annular wall 16 with a lateral outward curve 19, merging into a downward and inward curve 20, which continues into an inward upward curve 21 inside the curve 19, the curve 21 continuing into an upward and outwardly extending curve 22, thereby forming a double bead having an outer wall and an inner wall whose mating sides are arranged to be engaged by the annular tapering lip of the mouth of the can, the sides of said tapering lip being engaged by said side faces of said double-walled bead for forming four

2 closely-adjacent side faces pressing side-
wardly against each other in the same hori-
zontal plane. The outer face of the taper-
ing plug at its smaller diameter is arranged
5 to be received by and engaged with the in-
ner face of the cut edge of the tapering lip at its
smaller diameter, the plug in being forced into
the can expanding the wall of said mouth for
causing the said plug to find and form a close
10 fit with the inner face of said wall, extending
over a considerable belt vertically for form-
ing a wide belt of contact between the plug
and mouth. The inner bead at the upper
15 end of the plug acts with the outer bead at
said upper end for pressing the said lip be-
said beads and forming side contact-faces
with the sides of said lip for providing a
wide belt of contact to both sides of said lip
20 formed of side faces which form close union
with each other for making tight mating
side faces on both sides of said lip. The in-
ner bead also curling into the outer bead
forms a wide mouth 23 on the plug for the
25 reception for the lip of the can, the said mouth
contracting toward the inside of the outer
bead for forming the close union between the
side mating inside faces of said bead and the
side faces of said lip. After the plug has
30 been pressed home the outer edge of the cut
lip 8 will have changed its form and be pre-
sented outwardly from the longitudinal mid-
dle of the can by reason of finding its fit on
the tapering plug, the said upper edge of the
35 said cut lip preferably extending above the
horizontal plane of the shoulder 4 at the up-
per edge of the can-body, the said lip taper-
ing outwardly from the longitudinal middle
of the can above said plane after the plug is
40 seated and tapering upwardly from its base
and inwardly toward the longitudinal mid-
dle of the can below said horizontal plane
after the seating of said plug, the said lower
taper merging into the lower face of the semi-
45 bead 6. After the plug has been seated the
outer edge of the outer plug-bead preferably
takes against the shoulder 9 for forming an
additional seat or joint for closing the can
and pressing the inner bead between the wall
50 of the mouth of the can and said shoulder 9,
thereby forming six mating continuous an-
nular side faces closely adjacent at the upper
edge of the can, the said six faces being in
substantially the same horizontal plane. The
55 transverse web at the mouth of the can-body
forms a transverse strengthening structure
for preventing flexure of the can at its top.
The cut edges of said plug and rim portion
are projected in a common direction. The
60 double beading at the outer end of the plug
and the beading of the rim portion form a
triple combination bead curled in similar di-
rection.

For securely locking the plug within the
mouth of the can I laterally expand the lower
65 end of the tapering side wall of the plug for

forming a continuous annular rib 25, extend-
ing annularly and continuously about the
lower end of the plug, the said rib being lo-
cated in substantially the horizontal plane of
the metal forming the lower curl of the semi-
70 bead of the transverse web connecting the
wall of the mouth of the can with the side of
said can, thereby forming an exceptionally
strong construction in that the lower end of
the plug is expanded against transversely-ex-
75 tending metal. The rib 25 extends annularly
and continuously under the transverse
web of the mouth of the can-body and forms
a lock against the giving or retraction of the
80 plug from its seat on account of inward pres-
sure in the can, while permitting the removal
of the friction-plug with a wedging action by
the insertion of a knife or similar instrument
between the bead of the plug and top of the
85 can, constituting the same a friction-top can.
If desired, the groove 11 of the semibead 6
may be supplied with a suitable packing 26,
as shown in Fig. 5, for forming an additional
safeguard against leakage of the can, although
90 my improved construction is such as to make
such packing unnecessary, the closure in
practice having been found to be so secure
that oils and other liquids which it has been
95 found impossible to retain in other friction-
top cans without leakage are held in my im-
proved device without leakage, and the con-
struction of my improved device is such as to
permit materially larger packages to be made
100 with success with friction-tops than has here-
tofore been accomplished.

In my improved can-closure the expansion
of the metal of the parts is directed outwardly,
this expansion being a resilient expansion,
causing the parts to continuously exert an in-
ward pressure upon the joints for forming a
105 continuously-tight joint, and it has been
found in practice that if a vertical incision be
made by a fine-bladed saw in the top edge of
the can, passing through the beads, the slot
110 left by the saw will immediately close on re-
moval of the saw-blade by reason of the re-
siliency pressure exerted at all times upon the
joints between the plug and can-mouth.

Having thus fully described my invention,
what I claim as new, and desire to secure by
115 Letters Patent, is—

1. A friction-top can having a body whose
upper end is provided with an inwardly later-
ally projecting annular web merging into an
outwardly-projecting wall forming a mouth,
120 said web comprising a curve at the bottom of
said mouth, and a plug having tapering an-
nular wall and an upper outer double-curved
bead forming mating side faces facing each
other in the inside of said bead at said taper-
125 ing wall, the said wall of said body-mouth
taking between said mating side faces in the
inside of said double-curved bead of said plug,
the said plug provided with an annular con-
tinuous rib extending laterally outwardly im-
130

mediately below the said curve of said annular web of said body-mouth, substantially as described.

2. A friction-top can comprising a body whose upper edge is provided with an annular rim portion having an annular part projecting laterally and downwardly taperingly toward the longitudinal axis of the can and merging into an upwardly-opening semibead for forming an annular laterally inwardly extending strengthening-web having an annular shoulder therein and merging into an annular wall extending upwardly and taperingly toward the longitudinal axis of the can-body and being of frusto-conical shape and having an outer lip formed of the cut edge of the sheet metal composing said rim portion, said lip projecting above the horizontal plane of the upper edge of the can-body, and a plug having an annular wall tapering downwardly toward the longitudinal axis of the can-body in the form of an inverted frusto-cone having a connecting web at the smaller end thereof, and an outwardly-projecting outer double-

curl bead at the outer end thereof, the outer and inner curls of said double-curl bead forming adjacent side faces facing each other at the inner portion of said double-curl bead and forming an outwardly-flaring mouth at its bottom for receiving said lip, the outer edge of said bead taking against said annular shoulder in said rim portion, for forming six engaging annularly continuous side faces at the mouth of the can in substantially the same horizontal plane, the smaller end of the taper of said plug being expanded under the portion of larger diameter of the taper of the can-mouth for forming a rib in substantially the horizontal plane of said strengthening-web of said rim portion, substantially as described.

In witness whereof I have subscribed my name hereto in the presence of two subscribing witnesses.

JOSEPH J. MOSER.
